[57] CLAIM

The ornamental design for a soap holder, as shown and described.

DESCRIPTION

FIG. 1 is a front elevation of a soap holder incorporating our design, the upper and lower halves being shown separated one from the other;

FIG. 2 is an underside plan view of the upper half of the soap holder of FIG. 1;

FIG. 3 is an underside plan view of the lower half of the soap holder of FIG. 1;

FIG. 4 is a plan view of the upper half of the soap holder of FIG. 1;

FIG. 5 is a plan view of the lower half of the soap holder;

FIG. 6 is a front elevation of the soap holder with the two halves in assembled condition, the rear elevation being a mirror image of FIG. 6; and,

FIG. 7 is an end elevation of the soap holder, the opposite end being a mirror image of FIG. 7.
